WAVE GUIDE-COAXIAL ADAPTER

John S. Overholser, Los Angeles, Rex C. Bean, Bellflower, and Kenneth E. Wilcox, Los Angeles, Calif., assignors to Ta-Mar, Inc., Culver City, Calif., a corporation of California

Application March 10, 1958, Serial No. 49,968

Term of patent 14 years

(Cl. D26—1)

Fig. 1 is a side elevational view of a wave guide-coaxial adapter, showing our new design, the opposite side being substantially a mirror image thereof;

Fig. 2 is a front elevational view; and

Fig. 3 is a cross-sectional view thereof, taken on line 3—3 in Fig. 1.

The back, not shown, is conventional.

We claim:

The ornamental design for a wave guide-coaxial adapter, substantially as shown and described.
